UNITED STATES PATENT OFFICE.

EDWARD C. READEE AND VINCENT P. FINN, OF CLEVELAND, OHIO.

DRYING APPARATUS.

Application filed May 1, 1926. Serial No. 105,971.

This invention relates to drying apparatus,—and more particularly to apparatus for drying materials in a finely divided condition. The general object of the invention is to provide an apparatus of this character which will enable material to be dried efficiently and without danger of adhering to walls of the drying conduit through which it is conducted to the place of storage.

Another object of the invention is to provide a drying apparatus of the character described which is well adapted for drying finely divided food stuffs such as sugar and all kinds of condiments.

Another object of our invention is to provide an apparatus for drying finely divided edible material in which the material is dried without coming in contact with the products of combustion.

Another object of our invention is to provide a novel heating unit which is very efficient, yet simple in construction and which can be manufactured at a comparatively low cost.

Further and more limited objects of the invention will appear hereinafter and will be realized in and through the construction and arrangement of parts shown in the accompanying drawings in which Fig. 1 is a view in side elevation of my improved drying apparatus; Fig. 2 is a horizontal sectional view on the line 2—2 of Fig. 1; Fig. 3 is a vertical sectional view of the heating unit or furnace; and Fig. 4 is a view similar to Fig. 3 but taken at right angles thereto.

Describing the various parts by reference characters the numeral 1 designates our improved heating unit to which a combustible mixture is supplied by means of a plurality of gas or oil burners 2. The burners in the illustration shown herein are of the injector burner type having supply pipes 3 for oil and pipes 4 for delivering air under pressure thereto. The details of the burner construction form no part of our invention, it being sufficient for our purpose to use any one of the existing types of injector burners employing oil or gas and air under pressure.

5 denotes a blower supported on a suitable stand 6 and having a delivery pipe 7 connected with a hot air chamber 8 and a conduit 9 communicating with the upper end of the heating unit.

The heating unit comprises a base B having a combustion chamber 10, a heating chamber

11 and a fresh air supply chamber 12. A removable steel plate 10' separates the combustion chamber from the heating chamber and a plurality of conduits or passageways 11' connect the combustion chamber 10 with the heating chamber 11. A partition 12' separates the heating chamber from the fresh air chamber 12. The hot air chamber 8 is supported within the heating chamber 11 by means of suitable supports 13 and this chamber communicates with the fresh air chamber through passageways 14. A conduit or fume vent 15 communicates with the chamber 11. The fresh air chamber 12 is also provided with suitable vent openings 16. Communicating with the hot air chamber 8 is a conduit 17 which is of greater cross sectional area than the conduit 7, the purpose of which will hereinafter appear. The conduit 17 communicates at its opposite end with a receptacle 18 as shown in Fig. 1 and connects the hot air chamber with the receptacle 18. The material to be dried is delivered into the conduit 17 through a hopper 19 as shown in Fig. 1. The burners 2 are positioned adjacent one side of the combustion chamber and the conduits 11' conduct the products of combustion to the heating chamber 11 in which the hot air chamber 8 is supported. The conduit 15 conducts the products of combustion to the outside air.

With the parts constructed and arranged as described the chamber 10 will be heated by the burners 2, the air for the burners being preferably taken in from the conduit 7 by the pipe connections 4 controlled by suitable valves 4'. The blower 5 is driven from any suitable source of power, and the air will operate to atomize the oil or other liquid fuel in the manner usual with injector burners and the mixture will be burned within the combustion chamber 10, the products of combustion being delivered by means of the conduits 11' to the chamber 11, the blower 5 being connected with the upper end of the furnace by means of the conduit 9 and the furnace being provided with vent openings 16 as shown, air will be drawn from the upper part of the furnace and delivered through conduit 7 into the chamber 8. The conduit 17 being considerably larger than the conduit 7 and the conduit 7 being positioned as shown in Fig. 3 an injector action is obtained and the hot air from the chamber 8 is delivered into the conduit 17. The material to be dried is fed into the conduit 17 from the hopper 19 and this

conduit is preferably lined with laminated wood or a metal known as Alpax metal which prevents the food stuffs from becoming contaminated due to the contact with the interior of the conduit 17. The material to be dried being delivered into this stream of air and entrained by the action thereof will be thoroughly dried by the hot air and will be delivered by the blast into the container 18. The particles of the materials to be dried will be separated and thoroughly dried without adhering to the walls of the conduit.

If desired the container 18 may have connected therewith, by means of a conduit 20, a standard dust collecting apparatus. The dust being withdrawn by means of a suction fan 21 driven by a motor 22 and delivered to a dust collecting receptacle 23 from which the same may be withdrawn through a spout 24.

20 As shown in detail in Fig. 2 the container 18 is provided with a suitable lining 18' which prevents the same from becoming worn due to the particles being thrown against the interior wall of the container.

25 The apparatus shown herein has proven very successful and efficient in action and prevents the caking of the material to be dried and its adherence to the walls of the conduits and also effects a complete and rapid drying 30 of the material.

An important feature of our apparatus is that the material to be dried never comes in contact with the products of combustion from the furnace as the same would have an injurious effect upon the food stuffs to be dried.

35 It will now be clear that we have provided an apparatus which will accomplish the objects of the invention as hereinbefore stated.

Having thus described our invention, what 40 we claim is:

1. A heating unit for drying apparatus comprising, a fresh air chamber, combustion chamber and means for heating the same, a heating chamber having communication 45 with said combustion chamber, a hot air chamber supported within said heating chamber, a fume vent for said heating chamber, a pair of oppositely disposed conduits communicating with said hot air chamber and leading through opposite walls of said heating chamber, and means for withdrawing air 50 from said fresh air chamber and delivering the same through said pair of conduits.

2. A device as set forth in claim 1 having a

removable partition between said combustion 55 chamber and heating chamber.

3. A device as set forth in claim 1 having a conduit connecting said fresh air chamber and hot air chamber.

4. A device as set forth in claim 1 in which 60 one of said pair of conduits is of larger cross sectional area than the other.

5. A device as set forth in claim 1 in which said means for withdrawing air comprises a blower communicating at one end with said 65 fresh air chamber and at the opposite end with one of said pair of conduits.

6. In a heating unit for drying apparatus of the character described, the combination of a combustion chamber and means for heating 70 the same, a heating chamber having communication with said combustion chamber and vented to the atmosphere, a hot air chamber arranged within said heating chamber, a pair of conduits communicating with said hot 75 air chamber and leading outwardly therefrom, and means for delivering air through said heating chamber and conduits.

7. A device as set forth in claim 6 having a removable partition between said combustion 80 chamber and heating chamber.

8. A device as set forth in claim 6 in which one of said pair of conduits is of larger cross sectional area than the other.

9. In a heating unit of the character described, the combination of a combustion chamber and means for heating the same, of a heating chamber communicating with said combustion chamber and vented to the atmosphere, a hot air chamber disposed within said 90 heating chamber, an outlet conduit leading from said hot air chamber and an inlet conduit leading into said hot air chamber and having its delivery end disposed in alignment with the intake end of said outlet conduit and 95 means for delivering a blast of air through said conduits.

10. A heating unit as set forth in claim 9 in which said outlet conduit is of larger diameter than the delivery end of said inlet conduit. 100

11. A heating unit as set forth in claim 9 having a removable partition between said combustion chamber and the heating chamber.

In testimony whereof, we hereunto affix our signatures.

EDWARD C. READER
